No. 877,523.

PATENTED JAN. 28, 1908.

J. W. SMITH.
PNEUMATIC DRILL.
APPLICATION FILED APR. 6, 1907.

UNITED STATES PATENT OFFICE.

JOHN W. SMITH, OF PHILADELPHIA, PENNSYLVANIA.

PNEUMATIC DRILL.

No. 877,523.

Specification of Letters Patent.

Patented Jan. 28, 1908.

Application filed April 6, 1907. Serial No. 366,651.

To all whom it may concern:

Be it known that I, JOHN W. SMITH, a citizen of the United States, residing at Philadelphia, in the county of Philadelphia and 5 State of Pennsylvania, have invented certain new and useful Improvements in Pneumatic Drills, of which the following is a specification.

This invention relates to portable pneumatic drills and has for its object to provide a 10 drill compact in structure, durable, economical in the consumption of air, operative without vibration, and light in weight for a given capacity.

15 For this purpose, my invention consists of a pneumatic drill, comprising a drill spindle, a turbine wheel, and means for transmitting the rotary movement of the turbine wheel to the drill-spindle.

20 The invention consists further of a pneumatic drill, comprising a drill-spindle, a turbine wheel, a hollow power-shaft secured to the turbine wheel, a drill-spindle extractor passing through the power-shaft for extracting 25 the drill, and transmission means between the drill-spindle and the power-shaft.

The invention consists further of a pneumatic drill comprising two compartments, a 30 turbine wheel in one compartment, a drill-spindle, and means for transmitting the rotary movement of the turbine wheel to the drill-spindle, in the second compartment. And the invention consists further of certain 35 novel features which will be more fully described hereinafter and finally pointed out in the claims.

In the accompanying drawings, Figure 1 represents an end view of my improved pneumatic drill, Fig. 2 represents a vertical longitudinal section of Fig. 1 taken on line 2—2 of 40 Fig. 1, and Fig. 3, represents a detail view of the turbine shaft and drill-spindle extractor passing therethrough.

Similar letters indicate corresponding 45 parts.

Referring to the drawings, the casing A is provided with an inlet B, to which a supply 50 hose, not shown, may be conveniently secured, and also with outlets D¹. The head A¹ of the casing A is provided with an opening a¹, through which the feed-screw E¹ and drill-spindle extractor E passes. The feed 55 screw E¹ engages a threaded socket A³ of the casing-head A¹, and has secured at its outer end E³, by means of a key e, a feeding handle e¹ having arms e². At the inner end of the

feed screw, E¹ is secured, or made integral therewith, the drill-spindle extractor E. By the rotary movement of the handle e¹, the drill-spindle extractor E is moved inwardly of the casing. The other head A² of the casing A is provided with a tubular extension a² in which a spindle socket F is journaled. A drill-spindle F¹ is inserted in the drill-socket F and held therein, so as to 65 be rotated on the rotation of the socket F.

The drill extractor E is arranged to come in contact with the spindle when screwed to its innermost position, whereby the drill-proper F¹ may be extracted by means of 70 ejection. In the casing A is arranged a turbine G having U-shaped buckets H, which turbine has its disk g provided with a hub g¹, secured to a hollow shaft M. The U-shaped buckets are impinged by air guided by means of a nozzle H¹ and channels H², the operation of which being well known need not be specifically described, all the more so as any approved turbine system could be used equally well. A supply channel K connects the inlet B with the nozzle H¹. 75

Air is admitted to the turbine wheel by means of the nozzle or nozzles in communication with the inlet B. For the purpose of obtaining the highest efficiency some form of 80 spiral system or some other multiple impact system of turbine construction is made use of, which causes the air to be impinged against the turbine buckets several times before escaping to the exhaust. The accompanying drawing shows a spiral system, in 85 which the expanded air finally escapes at D¹.

The turbine shaft M is hollow to allow the passage of the drill-spindle extractor E, which extends from one head A¹ of the casing to the other, A², and which is journaled at the spindle end of the casing in the socket F. On the power shaft M a pinion n is secured, which meshes with gears n¹, each of which is mounted on a stud-shaft n², supported in the walls of the casing at n³ and n⁴. Enlarged parts n⁵ are provided, which have secured thereto pinions S, each of which mesh with the gear T, which is secured to the drill socket F. Both gears n¹ engage the pinion n, and both pinions S engage the gear wheel T. The object of this arrangement is to cause the torque of the power-shaft M to be balanced. 95 100 105

A socket t, is provided with a thrust-bearing t², between which and a bearing t¹ balls t³ are interposed. The thrust-bearing t² 110

may also be placed at the lower end of the drill-spindle and still be in communication with the oil from the oil-tight compartment, as the oil passing down the drill-spindle 5 would also lubricate the thrust-bearing.

The shaft M is provided with an annular groove m engaged by balls m^1 , which engage the grooves of the inner part of a bearing ring m^2 , which is provided also at its outer 10 portion with grooves, engaged by balls m^3 , which also engage the grooves of a stationary bearing m^4 . These novel bearings are intended to take the place of the plain ball-bearings ordinarily used. As the rotary 15 speed of a turbine rotor of such small diameter is very high, a plain ball-bearing will last but a short time. The bearing just described forms a twin-bearing, in which this excessive speed is divided between two bearings m and m^2 , each of which is constructed to revolve perfectly free, in which case the excessive speed will divide itself approximately equal between the two bearings, thus causing each bearing to operate at approximately 20 one-half of a single bearing. The small vibration which is common to bearings of high speed has a tendency to prevent one of these twin bearings from standing still while the other rotates.

30 The turbine g rotates in a compartment N^1 , separated from that in which the transmission mechanism is arranged. This compartment N^1 is separated from the mechanism compartment N^2 by means of the dividing wall P. The turbine compartment is in communication with the atmosphere by means of small holes D². In order to have a successful machine for running at such high speed, it is necessary to have the transmission 35 mechanism operate in oil or grease and for this reason an oil tight compartment N^2 is arranged. This, as is seen in the drawings, is formed by the casing A and the dividing wall P. Hence, a complete turbo-pneumatic drill consists of a suitable casing 40 with two compartments N^1 and N^2 , one of which, N^2 , is the oil tight compartment containing suitable transmission mechanism with all the bearings in communication with 45 suitable oil or grease, and the other, N^1 , is a separate compartment, in which the turbine rotor is mounted or in which a complete turbine is installed. These two compartments are so arranged that there is no communication 50 between them. Thus, chambers are formed, neither one of which communicates with the other and each of which is separated from the other. The oil compartment, in which the mechanism moves, being 55 oil-tight, no oil passes into the turbine compartment, and on the other hand, no air pressure can affect the oil compartment. As will be noticed the axis of the turbine-wheel is in line with that of the drill-spindle 60 F¹, they may also be parallel. The advan-

tage of this is two-fold, first, it allows a suitable pin or drill extractor to pass through the turbine-shaft, and secondly, it admits a compact design.

In the construction of pneumatic drills of former types such as the piston or rotor, both the power and transmission mechanism were arranged in a single compartment, which contained a suitable lubricant. Fluctuation of the air-pressure had a tendency 70 to drive the lubricant out, so in actual practice no supply of lubricant could be maintained. This is especially the case in rotor and piston-types.

Among the advantages of my improved 80 construction are that my improved pneumatic drill is more economical in the consumption of air than the air-drill of the piston type or rotor type hitherto used; secondly, it is more durable, thirdly, it operates without vibration, fourthly, the air consumption does not increase with the time the machine has been in operation, and fifthly, the machine as a whole is lighter in weight in proportion to its capacity than other machines 85 hitherto used, and at the same time is cheaper to manufacture. The field of usefulness of a pneumatic drill is not limited to drilling holes only, but is applied to every service in which a portable motor is found 90 convenient, such as reaming, tapping, grinding, rolling tubes and driving various machines.

In the accompanying specification, I have shown the most popular means for attaching drills, reamers and the various other tools to be driven. The means referred to is a standard drill socket. But these pneumatic drills may be fitted with suitable chucks on the spindle if so desired.

Having thus described my invention, I claim as new and desire to secure by Letters Patent:

1. A pneumatic drill comprising a drill-spindle, a turbine wheel with buckets, a power-shaft secured to the turbine-wheel, a drill extractor passing through the power-shaft for extracting the drills, and transmission means between the drill-spindle and the power-shaft.

2. In a pneumatic drill having a drill-spindle, a casing having two compartments, a turbine-wheel compartment and an oil-tight compartment containing a lubricant, a turbine-wheel having buckets in the turbine-wheel compartment, a power-shaft secured to said turbine-wheel, and bearings for the power-shaft, all the bearings of the power-shaft in the oil-tight compartment, being all the bearings of the turbine, being in communication with the lubricant therein.

3. In a pneumatic drill having a drill-spindle, a casing having two compartments, a turbine-wheel compartment and an oil-tight compartment containing a lubricant, a

turbine-wheel having buckets in the turbine-wheel compartment, transmission mechanism between the turbine-wheel and drill-spindle, and bearings for the turbine-wheel 5 and the transmission mechanism, all of said bearings being in communication with the lubricant in the oil-tight compartment.

4. In a pneumatic drill having a drill-spindle, a casing having two non-communicating compartments, a turbine-wheel compartment and an oil-tight compartment containing a lubricant, one separated from the other, a turbine-wheel having buckets in the turbine-wheel compartment, transmission

mechanism and gears between the turbine-wheel and drill-spindle, and bearings for the turbine-wheel and for the transmission mechanism and gears, all of said bearings and gears being in communication with the lubricant in the oil-tight compartment. 15 20

In testimony, that I claim the foregoing as my invention, I have signed my name in presence of two subscribing witnesses.

JOHN W. SMITH.
